UNITED STATES PATENT OFFICE.

VINCENT MRASEK, OF BURBANK, FLORIDA.

STOVEPIPE-SHELF.

1,239,938.

Specification of Letters Patent. Patented Sept. 11, 1917.

Application filed June 19, 1916. Serial No. 104,594.

To all whom it may concern:

Be it known that I, VINCENT MRASEK, a citizen of the United States, and a resident of Burbank, in the county of Marion and

5 State of Florida, have invented an Improvement in Stovepipe-Shelves, of which the following is a specification.

10 My invention is an improvement in stove pipe shelves, and has for its object to provide a shelf of the character specified, suitable for supporting a tea or coffee pot, and wherein the shelf may be collapsed for transportation, and wherein adjustable means is provided for engaging the pipe to support 15 the shelf in any desired position thereon.

In the drawings:

Figure 1 is a perspective view showing the improvement in use.

20 Figs. 2 and 3 are sections on the lines 2—2 and 3—3 of Fig. 1, respectively, each figure looking in the direction of the arrows adjacent to the line.

25 Fig. 4 is a perspective view of the shelf detached.

30 The embodiment of the invention shown in Figs. 1 to 4 is arranged on the vertical portion 1 of the pipe which connects the range 2 with the flue 3, and the improved shelf comprises a plate 4 of metal, having its side edges flanged, as shown at 5, and having at its front end a bearing 6. The opposite end of the plate is recessed or concave, as shown at 7, to fit around the pipe, and a frame of wire is connected with the 35 bearing 6. This frame consists of side mem-

bers 7, an end member 8 which is journaled in the bearing 6, and an end member 9 which is concave to fit the pipe, as shown more particularly in Fig. 3.

40 A brace 10 is arranged between the end member 9 and the recessed end of the plate, the said brace being bent around the end member 9 at one end, and having at the other end tongues 11 which are passed through a slot in the plate, and the tongues 45 are bent in opposite directions to prevent disengagement of the brace. The plate 4 is provided at the concave end 7 with a depending tongue 12 for engaging a sectional ring 13—13^a encircling the pipe. 50

I claim:

55 A stove pipe shelf comprising a plate recessed at one end to fit the pipe and having at the other end a bearing, a substantially rectangular frame journaled at one end in the bearing and shaped at the other to fit the pipe, a brace between the said end and the plate, the plate having a depending tongue at the said end, said brace and tongue being flat strips tending to prevent lateral 60 movement, and means for connecting the shelf to a pipe, said means comprising a ring between which and the pipe the tongue engages, the ring being adjustable to permit it to be engaged with different sizes of pipes. 65

VINCENT MRASEK.
